UNITED STATES PATENT OFFICE

2,530,317

TOY EXPLOSIVE

Everett Storey, Chicago, Ill.

Application May 25, 1944, Serial No. 537,231

1 Claim. (Cl. 102—37)

1

This invention relates to a toy explosive which realistically simulates various implements of warfare, such as a ship, a bomb, etc.

An object of the invention is to provide a toy explosive which is caused to explode at the desired time by the chemical action of water within the device. Another object is to provide a device having a brittle shell and containing metallic sodium, the shell being designed to explode and shatter when water is permitted to enter and react with the sodium.

A more specific object is to provide a toy explosive in the form of a boat and which when inverted or immersed in a body of water will explode through chemical reaction caused by the water on the interior of the boat. Another specific object is to provide such a toy explosive simulating a depth bomb which will sink in a body of water and which when it reaches a predetermined depth will explode. A further object is to provide such a toy depth bomb which can be adjusted to explode at various depths. Another object is to provide a toy aerial bomb which can be dropped against an object which when it strikes will explode, the explosion being set off through chemical reaction on the interior of the bomb.

The invention is illustrated by the accompanying drawings, in which—

Fig. 1 is a sectional view in elevation showing the explosive in the form of a boat; Fig. 2 is a view partly in section showing the explosive in the form of a depth bomb; Fig. 3 is an enlarged sectional view, the section being taken at line 3—3 of Fig. 2; Fig. 4 is a view partly in section showing the explosive in the form of an aerial bomb; and Fig. 5 is a fragmentary sectional view of the form shown in Fig. 4 showing the device in condition for explosion.

As illustrated in Fig. 1, the toy explosive in the form of a ship comprises a casing including a lower portion or shell 10 simulating the hull of a ship. A top or deck portion 11 completes the closure and is provided with various appurtenances simulating the different visible equipment of a ship, the mast 12, the smokestack 13, etc.

The casing may be made of any suitable material, but preferably should be formed of an easily broken material, such as a resinous plastic, so that when the explosion takes place the structure will break easily. The lower portion or shell 10 should be imperforate and the interior hollow so that when the toy boat is placed on a body of water it will float, supported by this shell portion. However, the material from which the cas-

2

ing is formed should preferably be heavier than water, so that when the boat is filled with water it will sink.

On the interior of the boat and resting on the bottom is a piece of metallic sodium 14. The piece of sodium may take any form or shape, and may be coated with a film of oil 15 or other coating material to protect the metal from deterioration by contact with the air.

10 In the top 11 of the boat are a number of openings, one opening 16 in the fore part of the boat, and the openings 17 and 18 aft. It will be seen that the casing forms a complete closure except for these openings. While there are here 15 shown three such openings, it is understood that there may be any number of openings or perforations. The function of the openings is to admit water to the interior of the boat when the boat is upturned or immersed.

20 In use, the boat may be placed on a body of water, such as in a tub, basin, pond or stream, and when in a game, or make-believe warfare, the boat is struck or in any way is caused to take water through either of the openings 16, 17 and 25 18, a series of events are started which result in the boats being exploded.

When the water comes into contact with the metallic sodium 14 on the boat's interior, the water reacts violently with the sodium to produce 30 hydrogen gas. The hydrogen gas makes with the oxygen of the air inside the boat an explosive mixture. This reaction between the water and sodium produces a heat which is sufficient to 35 ignite the sodium and serves to set off the explosion of the hydrogen-oxygen mixture. As a result of the explosion, the casing is ruptured, and the boat sinks.

As illustrated in Figs. 2 and 3, the invention takes the form of a depth bomb. The casing is 40 formed in two pieces and is preferably made of a resinous plastic material which is quite brittle so that upon explosion it will burst into fragments. The nose portion 20 is provided at its top with a circular band 21 having a number of 45 spaced apertures 22. Below the band 21 is a circular groove 23, and four grooves 24 equally spaced about the circumference of groove 23 lead from this circular groove to the top edge of the band. As will later appear more clearly, the 50 function of grooves 23 and 24 are to cooperate with lugs on the other part of the casing to secure the two parts together.

The upper part 30 of the casing has a narrowed rear end portion 31 to which are attached the 55 laterally-extending vanes 32. These vanes serve

to guide and direct the bomb as it is dropped through the air or water. On the lower edge of the part 30 is a circular lip 33 having four equally-spaced inwardly-extending lugs 34. This lip is provided with a number of spaced apertures 35, the size and spacing of which correspond with the size and spacing of the apertures 22 in the band 21. In assembling the parts 20 and 30, the lip 33 of the part 30 is placed downwardly over the band 21 of the other part, with the lugs 34 passing through the vertical grooves 24. Then with the lugs 34 in register with the circular groove 23, the parts may be turned relative to each other to lock the structure in assembled form. When the parts are in the relative angular position illustrated in Fig. 3, the openings or apertures 35 and 22 are in complete register so that maximum size passages are provided. If the parts are turned slightly, the passages leading to the interior of the bomb are slightly decreased, and if the parts are turned further the passages to the interior may be completely closed. A set screw 36 is provided to secure the parts in any desired angular position with respect to each other.

The interior of the depth bomb casing, like the boat casing, is hollow and contains air and a piece of metallic sodium. Before the bomb is to be used, it may have its parts turned so that the opening into it is closed to prevent deterioration of the sodium. When the bomb is to be used, the parts are adjusted to the desired opening and the set screw tightened. It may be dropped into a body of water and will sink. As it sinks, the water will come through the openings 35 and 22 to the extent that these openings are in register, and as the water comes into contact with the metallic sodium an explosive gaseous mixture will be generated and exploded, as explained in connection with the embodiment illustrated in Fig. 1.

The depth to which the bomb will descend in the water before sufficient water enters to explode the bomb can be regulated by turning the parts as heretofore explained to permit a slower or faster entrance of water into the casing. By thus increasing the size of the passages into the bomb, the bomb will be caused to explode at a more shallow depth, and by decreasing the size of these packages, the bomb can be made to explode at a greater depth.

The embodiment of the invention illustrated in Figs. 4 and 5, is intended to simulate an aerial bomb. The outer casing 40 may be of the same general form and shape as the bomb of Figs. 2 and 3, except that it may be formed in one piece if desired.

On the interior of casing 40 is a second casing 50 which contains the piece 51 of metallic sodium, and also contains air or other oxygen containing gas. This second casing may be supported within the first casing by the arms 52 extending between the casings.

In the space between casings 40 and 50 is contained a hydrogen-oxygen liquid, such as water or hydrogen peroxide or the higher peroxides.

Extending through the outer casing 40 at the nose thereof is a pin 41 having a point 42 extending toward the inner casing. This pin may be sealed with the outer casing with cement 43 or other material suitable for making a liquid-tight seal between the pin and the casing.

In use, the bomb device of Figs. 4 and 5 may be dropped through the air at any objective, and as it passes through the air the vanes 44 keep the bomb pointed straight. As the bomb strikes, the pin 41 will be pushed in, as illustrated particularly in Fig. 5, to puncture or break the inner shell 50. This permits the water or peroxide about the shell 50 to enter and come into contact with the metallic sodium. Upon contact of the water with the sodium, a chemical reaction occurs, as heretofore explained, and an explosion results which shatters both of casings 40 and 50, throwing liquid in all directions.

Instead of metallic sodium, any metal of the class consisting of the alkali metals and the alkaline earth metals may be used in the device of the invention, for example, potassium, lithium, magnesium, barium or strontium. Sodium, however, is to be preferred since it is readily available commercially and reacts sufficiently violently with water while at the same time reacts sufficiently slowly in air that with a protective film of oil or the like as described, it may be preserved even in air.

Although the invention has been described in connection with particular embodiments, it will be apparent that changes and modifications may be readily made without departing from the spirit and scope of the invention.

I claim:

A toy explosive comprising a casing containing on its interior air and alkali metal, said casing and its contents being heavier than an equal volume of water so that the casing will sink in a body of water, said casing having overlapping wall portions, each of which is provided with an opening, said portions being movable with respect to each other to bring the openings of said portions into different degrees of registry with each other, said openings permitting the entry of water into contact with said metal to provide with said air an explosive mixture.
